UNITED STATES PATENT OFFICE

146,151

DESIGN FOR A PROJECTOR

Otto Rudolf Nemeth, Chicago, Ill., assignor to Otto R. Nemeth, Inc., Chicago, Ill., a corporation of Delaware

Application June 27, 1946, Serial No. 131,066

Term of patent 14 years

(Cl. D61—1)

To all whom it may concern:

Be it known that I, Otto R. Nemeth, a citizen of the United States, residing at Chicago, Illinois, have invented a new, original, and ornamental Design for a Projector, of which the following is a specification, reference being had to the accompanying drawings, forming part thereof.

showing my new design;

Figure 2 is a side elevational view; and

Figure 3 is a front elevational view thereof.

I claim:

The ornamental design for a projector, as shown.

OTTO R. NEMETH.
